UNITED STATES PATENT OFFICE

164,162

COMBINATION HELICOPTER AND AUTOMOBILE

Albert E. Fry, Los Angeles, Calif.

Application March 27, 1950, Serial No. 8,800

Term of patent 14 years

(Cl. D71—1)

To all whom it may concern:

Be it known that I, Albert E. Fry, a citizen of the United States, residing at Los Angeles, in the county of Los Angeles and State of California, have invented a new, original, and ornamental Design for Combination Helicopter and Automobile, of which the following is a specification, reference being had to the accompanying drawing, forming part thereof, in which:

Fig. 1 is a side elevational view of a combination helicopter and automobile, showing my new design;

Fig. 2 is a front elevational view taken from the left of Fig. 1;

Fig. 3 is a rear elevational view taken from the right of Fig. 1; and

Fig. 4 is a top plan view.

I claim:

The ornamental design for a combination helicopter and automobile, as shown.

ALBERT E. FRY.
